(57) **CLAIM**

The ornamental design for a sensor weather seal as shown and described.

DESCRIPTION

FIG. 1 is a perspective view of one embodiment of the sensor weather seal design of the present invention;

FIG. 2 is a front view of the sensor weather seal of FIG. 1; FIG. 3 is a left-side view of the sensor weather seal of FIG. 1;

FIG. 4 is a right-side view of the sensor weather seal of FIG. 1;

FIG. 5 is a bottom view of the sensor weather seal of FIG. 1;

FIG. 6 is a top view of the sensor weather seal of FIG. 1; FIG. 7 is a sectional view of the sensor weather seal along line 7-7 of FIG. 6 with a distinction showing two different materials thereof; and,

FIG. 8 is a front view of another embodiment of the sensor weather seal, with an alternate internal detail.

1 Claim, 2 Drawing Sheets
